UNITED STATES PATENT OFFICE.

JOHN A. SANDER, OF NEWARK, NEW JERSEY.

MEAT-CUTTER.

SPECIFICATION forming part of Letters Patent No. 650,618, dated May 29, 1900.

Application filed November 3, 1899. Serial No. 735,671. (No model.)

To all whom it may concern:

Be it known that I, JOHN A. SANDER, a citizen of the United States, residing at Newark, in the county of Essex and State of New Jersey, have invented certain new and useful Improvements in Meat-Chopping Machines; and I do hereby declare the following to be a full, clear, and exact description of the invention, such as will enable others skilled in the art to which it appertains to make and use the same, reference being had to the accompanying drawings, and to letters and numerals of reference marked thereon, which form a part of this specification.

This invention relates to certain improvements in that class of meat-chopping machines represented by my prior patent, No. 249,405, issued November 8, 1881, the objects of the present invention being in general to provide means for more easily and effectively controlling the action and position of the vertical rotary shaft, which carries at its lower end the revolving cutters or knives, their spindles, and coöperating parts. More specific objects are to enable the rotary shaft to be quickly thrown out of connection with the driving means and thus stopped, to provide means for moving the rotary shaft vertically while in motion, and thus changing the position of the cutters with relation to their work and to secure means for temporarily locking the said shaft in any desired position, to enable the vertical adjustment of the rotary shaft and the locking to be done in one operation, and to secure other advantages and results, some of which may be hereinafter referred to in connection with the description of the working parts.

The invention consists in the improved meat-chopping machine and in the arrangements and combinations of parts of the same, all substantially as will be hereinafter set forth, and finally embraced in the clauses of the claim.

Referring to the accompanying drawings, in which like letters and numerals of reference indicate corresponding parts in each of the several views, Figure 1 is a perspective view of my improved machine complete. Fig. 2 is a central sectional view taken through the vertical rotary shaft, its controlling-lever,

and associated parts on line *x*, Fig. 4. Fig. 3 is an enlarged side view of a portion of the same, showing more clearly the means for locking said controlling-lever; and Fig. 4 is a plan of the controlling-lever and its connections to the shaft, the shaft being shown in section on line *y*, Fig. 2.

In said drawings, *a* indicates a suitable base, and *b* is a standard or post providing at its upper end *b'* bearings for a horizontal driving-shaft *c* and a vertical shaft *d*, adapted to receive motion from the horizontal shaft *c* through coöperating bevel-gears *e f*. Fast and loose pulleys *g' g²* and a belt-shifter *h* are provided at the opposite or rear end of the horizontal shaft *c*, by means of which power to drive said shaft is obtained in any usual manner. The middle portion of this shaft *c* carries a worm *i*, which meshes into a worm-wheel *j*, fast on the upper end of a downwardly-extending shaft *j*, which imparts, through gearing *j²* at its lower end, a slow rotary movement to the meat-block *k* in any well-known manner. Said block *k* is of ordinary construction, provided with a peripheral flange or rim *k'*, and eccentrically pivoted with respect to the vertical rotary shaft *d*, as is common. The lower end of said shaft *d* reaches to a point adjacent to the upper surface of the meat-block, and to said lower end of the shaft is fixed a cross-frame *l*, carrying the pivotal knives or cutters *l'* and a hood or guard *l²*, as has been usual heretofore.

It will be understood that the knives *l'*, carried by the shaft *d*, coöperate with the block *k* to secure a chopping of the meat or the like, and it is in the means next to be described for controlling the rotation and position of the shaft *d* that the present invention particularly inheres.

At a point just above the lower bearing *m'* of the shaft *d* in the frame *b'* I place upon said shaft a loose collar *2*, carrying the gear-wheel *f*, which intermeshes with the coöperating gear-wheel *e* on the horizontal driving-shaft *c*. The upper end of said collar is formed into a clutch member adapted to engage with a correspondingly-formed coöperating member *3*, firmly fixed upon the shaft *d* at a higher point by means of a set-screw *31* or equivalent means.

Above the clutch member 3 and resting at its lower end thereupon is a sleeve 4, loose upon the shaft d and extending through the upper bearing m^2 in the frame b' . A collar 5 and set-screw 51 above the sleeve 4 enables said sleeve to be held against longitudinal movement away from the clutch member 3. The bearing m^2 , through which the sleeve 4 extends, is slotted at the front and provided 10 with a rectangular longitudinal extension or enlargement 6, and on the corresponding side of the sleeve 4 is formed a rack 41, with teeth 42, which projects into the chamber or space 6. Said rack 41 and rack-chamber 6, aside 15 from their primary purpose hereinafter set forth, serve to key the sleeve 4 to the bearing m^2 and prevent rotation with the shaft d .

The front wall of the rack-chamber 6 is vertically slotted, as at 7, and parallel ears 8 20 project forwardly on either side of said slot. Between said ears is pivoted the disk-like head 9 of the controlling-lever, said head presenting at its inner side a segmental toothed portion 91, engaging the rack 41, and at the 25 opposite outer side providing a socket 92 to receive the handle-rod 10, provided at its outer end with a handle 11. By operating said controlling-lever either up or down in a vertical plane it will be understood that the 30 toothed end 91, intermeshing with the rack 41 on the sleeve 4, which sleeve is longitudinally fixed on the rotary shaft d between the collar 5 and clutch member 3, forces said rotary shaft either downwardly or upwardly 35 without interfering with its freedom to rotate.

The clutch members 2 3 are preferably formed with long engaging jaws, so that considerable vertical movement of the shaft d is allowed without disengaging the clutch members. This permits the cutters at the lower 40 end of the shaft to be adjusted to positions at different distances from the block. Extreme upward movement of the shaft d by the controlling-lever, however, draws the upper 45 clutch member 3 away from the lower member and permits the gear-wheel j to rotate idly on the shaft, as will be understood. This construction enables the cutters to be stopped without shifting the belt and thus 50 stopping the entire machine, so that the block k may continue to rotate while the cutters are stationary.

The collars 5, sleeve 4, and clutch member 3 can be fixed at any point on the shaft d by 55 the set-screws 51 or equivalent means if a greater change of position of the cutters relative to the block is required than is given by the controlling-lever.

To enable the controlling-lever, and thus 60 the rotary shaft, to be fixed temporarily in any of its various positions, I place upon the handle-rod 10 a sleeve 12, loosely inclosing said rod and abutting at its outer end against the handle-piece 11, which handle-piece 65 screws upon the end of the rod 10, as shown in Fig. 2. To the inner end of the sleeve 12 is attached, by screwing or the like, a forked

brake or clamping-piece 13, centrally and longitudinally perforated to slide upon the rod 10 and having its two prongs 131 131 lying 70 one each side of the head 9 and shaped at their extremities to fit against the projecting ears 8 8. Thus by screwing the handle-piece 11 onto the rod 10 when in engagement with the sleeve 12 the clamping-piece 13 is forced 75 against the ears 8 8 and the controlling-lever clamped against pivotal movement.

By having the handle work upon the rod 10 by a quick-acting screw-thread it will be seen that by grasping said handle in one hand 80 the controlling-lever may be given a pivotal movement to adjust the rotary shaft d and then by a twist of the hand locked in its new position.

Various unimportant changes may be made 85 from the exact construction which I have described without departing from the spirit or scope of the invention, and I do not wish to be understood as limiting myself by the positive descriptive terms employed except as the 90 state of the art may require.

Having thus described the invention, what I claim as new is—

1. In a meat-chopping machine, the combination of a block, a horizontal driving-shaft, 95 a vertical rotary shaft having cutters at its lower end, a clutch member loose on said vertical shaft and carrying a gear-wheel intermeshing with another gear-wheel on the driving-shaft, a clutch member, and a collar rotating with the shaft, a non-rotating sleeve arranged upon the shaft between said fixed collar and clutch member, and means for raising and lowering said sleeve, substantially as set forth. 100

2. In a meat-chopping machine, the combination with a driving-shaft, of a vertical shaft carrying cutters at its lower end, a clutch member loose on said vertical shaft and carrying a gear-wheel intermeshing with another gear-wheel upon the said driving-shaft, a co-operating clutch member fast on the shaft, a sleeve loose upon the shaft and keyed in its bearing or box, and having rack-teeth at one side, means for preventing longitudinal movement of said sleeve independent of the shaft, and a pivoted controlling-lever having a segmental pinion at the end engaging said rack on the sleeve, substantially as set forth. 115

3. In a meat-chopping machine, the combination with suitable bearings, of a vertical rotary shaft carrying cutters at its lower end, a clutch member loose on said shaft and provided with means for receiving power from any suitable source, a co-operating clutch 120 member fast on the shaft, a non-rotary sleeve, held against longitudinal movement on said shaft, said sleeve lying in one of the shaft-bearings and having a rack projecting into a groove or recess in said bearing, and a pivoted lever having at its end teeth engaging said rack, substantially as set forth. 130

4. In a meat-chopping machine, the combination with the bearings m' , m^2 , of the rotary

shaft d , fast and loose clutch members on said shaft, a sleeve held against longitudinal movement on the shaft and against rotary movement in the bearing m^2 , said sleeve presenting at one side a series of rack-teeth, a pivotal controlling-lever engaging said rack-teeth to raise or lower the sleeve, and means for clamping said lever in any angular position, substantially as set forth.

10. 5. The combination with the bearing m^2 , having a groove or recess at one side slotted at the front, the rotary shaft d , and the sleeve 4, having at one side a rack lying in said groove and provided with teeth, of a controlling-lever pivoted on the front of the bearing m^2 , and having its inner end entering the said slotted recess and engaging the rack, and clamping means upon said lever for engaging the bearing in which said lever is pivoted, substantially as set forth.

15. 6. The combination with a pivoted controlling-lever, of a clamping member supported upon said lever and adapted to slide longitudinally of the lever, and means for forcing 25 said clamping member into frictional contact with the fulcrumal bearings of the lever to lock said lever against pivotal movement, substantially as set forth.

20. 7. The combination with the herein-described controlling-lever pivoted between ears 8, 8, of a clamping member sliding longitudinally upon said lever, and means for forcing said clamping member into engage-

ment with the said ears, substantially as set forth.

25. 8. The combination with a controlling-lever pivoted in suitable bearings and having a threaded shank or rod and a handle screwing thereon, of a sleeve placed loosely upon said shank and abutting at its outer end against the said handle, said sleeve carrying at its inner end a clamp member adapted to be forced against the bearings of the lever, substantially as set forth.

30. 9. The combination with a controlling-lever pivoted in a suitable support and having a threaded shank, of a sleeve longitudinally movable on said shank and having its inner end adapted to engage the fixed support of the lever and a handled nut screwing on said shank to force the sleeve into clamping engagement, substantially as set forth.

35. 10. The combination with a pivoted controlling-lever having a handle adapted to rotate, of a clamping member sliding longitudinally upon said lever and adapted to be forced against the fulcrumal bearings of the lever by a rotary movement of said handle, substantially as set forth.

40. In testimony that I claim the foregoing I have hereunto set my hand this 26th day of October, 1899.

JOHN A. SANDER.
